UNITED STATES PATENT OFFICE.

CHARLES J. WATTERS, OF PHILADELPHIA, PENNSYLVANIA, ASSIGNOR TO NORTH AMERICAN LACE COMPANY, OF PHILADELPHIA, PENNSYLVANIA, A CORPORATION OF PENNSYLVANIA.

DESIGN FOR A LACE.

48,660.

Specification for Design.

Patented Feb. 29, 1916.

Application filed December 10, 1915. Serial No. 66,202. Term of patent 3½ years.

To all whom it may concern:

Be it known that I, CHARLES J. WATTERS, a subject of the King of Great Britain and Ireland and the Isle of Man, and a resident of Philadelphia, county of Philadelphia, State of Pennsylvania, have invented a certain new, original, and ornamental Design for a Lace, of which the following is a specification, reference being had to the accompanying drawing, forming part thereof, in which the figure is a plan view of a portion of lace illustrating my new design.

I claim:—

The ornamental design for a lace, substantially as shown.

CHARLES J. WATTERS.

Witnesses:

JOHN J. KELLY,
ROBERT H. LAIRD.
